UNITED STATES PATENT OFFICE.

CHAUNCEY B. FORWARD, OF URBANA, OHIO.

APPARATUS FOR TREATING CRUDE PETROLEUM AND THE DISTILLATES THEREOF.

1,247,808.

Specification of Letters Patent. Patented Nov. 27, 1917.

Application filed September 15, 1915. Serial No. 50,759.

To all whom it may concern:

Be it known that I, CHAUNCEY B. FORWARD, a citizen of the United States, residing at Urbana, in the county of Champlain and State of Ohio, have invented certain new and useful Improvements in Apparatus for Heating Crude Petroleum and the Distillates Thereof, of which the following is a specification.

10 My invention has reference to an apparatus for treating crude oil and the distillates thereof and is an improvement on my Letters Patent of the United States No. 1,088,693, March 3, 1914, and Letters Patent

15 No. 1,181,301, of May 2, 1916.

In my present invention, I have so far improved on the apparatus set forth in said patent that the light distillates are delivered in a more purified state than formerly and 20 there is a largely increased percentage in the volume of the ultimate output and particularly of the naphtha and gasoline series, as will presently be seen.

In the accompanying drawings, Figure 1 25 is an elevation of my apparatus more or less diagrammatic and showing the retort in longitudinal section. Fig. 2 is an elevation in enlarged section of one of the intermediate condensers which is provided with reheat- 30 ing means as hereinafter fully described.

By the means thus shown, I am enabled to purify the fractional distillates obtained from these portions of crude oil after the heavier fractions or oils have been previ- 35 ously condensed as shown substantially in my said Patent No. 1,088,693 as well as being enabled to obtain a materially increased percentage of the more volatile or lighter products of the oil as above indicated.

40 In my said Patent No. 1,088,693, I state that the several condensers may be changed in size and numbers and made smaller or larger here and there in the series according to the character of the oil and the number 45 and character of the fractions desired therefrom, and some of these possibilities and changes structurally are present in this case, plus the changes necessary to secure the further results herein described.

50 Thus, the drawings show a retort R and a series of condensers D, E, F, G, H, I, and K and a condenser worm L connected and operating in the order named. Discharge is from the top of one condenser to the bottom 55 of the next in order, as formerly, by a pipe

2, and a drain 3 for the condensed products from each by the trap or outlet 4.

Formerly, the operation was progressive and similar in manner from one condenser to the other, the initial pressure from or 60 through the retort itself being exclusively relied upon to drive the fluid vapors through the series of condensers to the worm L, leaving condensations in each according to the size of the columns and their position in the 65 series. Of course, the successive condensations passed off through the successive traps or outlets 4, as they do so in this case, but I have found it desirable to add a further treatment to the lighter distillates after the 70 heavier oil vapors have been condensed, and to this end I have provided the condenser column G in the series with a jacket J superheated by steam through branch pipe 7' from main pipe 7, and a superheated steam 75 jet 6 at the end of pipe 7 discharging into the bottom of said condenser column. Thus the heat in both the said column and the jacket about the same will be at about the same temperature as the retort, say 650 F., 80 less the comparatively slight loss by radiation *en route*, but the steam may be taken from any other available source.

The effect of said jet on the oil vapors at this point is to break them up into still more 85 minute particles and assist in the reheating of the same in connection with the superheated steam about said condenser column G. If desired, a fine wire mesh may be placed over the central opening at the bot- 90 tom of condenser G to further assist in the breaking up of the vapors at this point. The result of this operation is the purification of the distillates and at the same time an increased percentage of volatile oils con- 95 densed with the naphtha and gasoline. This increase however, in the naphtha and gaso- lene, is secured at a cost of a reduction in the amount of heavier oils, the vapors of which have been treated by the above im- 100 proved method. By reason of the action of the steam jacket and jet on the vapors in condenser G, there will be comparative little condensation, although there is some, and it will be observed that the bottom of the said 105 column is constructed so as to catch what- ever condensation does occur and trap the same off from the opening to the side of the center hole instead of from the central open- ing as in the other condenser columns, and 110

a pipe 10 connects with said bottom and has the usual trap or outlet 4.

On account of the increased temperature of the vapors as they come from condenser G by reason of the steam jacket J and the injection of steam therein, it is necessary to make the condenser H relatively larger so as to secure the condensation of the desired amount of the distillate that the operator wishes to obtain at this point in the operation. If, say—Ohio crude oil is being handled, the distillates coming from both the jacketed condenser G and the condenser H will be what is known as intermediate gas or fuel oil although the quantity of this distillate is less than is secured by the apparatus shown in my Patent No. 1,088,693 of March 3, 1914. The reason for the increased condensing area required at this point, as shown in this improved apparatus over said patent, is because of the increase in the temperature of the vapors in condenser column G, necessitating the larger condensing surface to secure the desired amount of condensation of the required gravity of distillate. The condenser I is relatively smaller by reason of the decreased amount of kerosene secured by this improved method, while condenser K is correspondingly larger by reason of the increased amount of naphtha obtained as well as condenser L for the gasoline.

I have shown the middle condenser in the series of seven with superheating means for the vapors which are uncondensed at that point in the process, but for that matter, it might be one or another of the said condensers and the degree of heat may be varied according to the results desired. So also may the individual condensers be varied as to elevation or length, it being understood that all are built in sections and adapted to be used as described and claimed in my patent above recited.

As the oils from the different oil fields are all different in character, it is obvious that it would be necessary for one to be skilled in the art in order to know at which point to place the steam jacketed condenser as well as to determine the size and number of condensers to be used according to the oil being treated and the number of fractions desired in each case.

When starting operations all the valves *v*

from the outlets or traps from the several condensers are closed and are kept closed until the said traps or goose necks 4 are filled and then they are opened. This avoids the possible blowing out of uncondensed vapors in the several condensers until said traps are filled and it also helps to equalize the pressure throughout the series. It will be seen that the final condenser or worm L has a valve or cock *v* the same as those preceding. After all the valves are opened there will be a sustained flow from the several condensers according to their respective gravities and condensation and discharges are contained without cessation throughout the period of operations.

Incident to the foregoing but not of the present invention, I show certain devices in diagram in Fig. 1, as a pump 20, or its equivalent, to force oil into the retort by pipe 21, and means indicated by 22 and pipe 23 to convey steam or air under pressure to atomize the oil to the retort. The pipe 24 is intended to convey steam from any available source to the jacket or drum *d* about the retort.

What I claim is:

1. An apparatus as described comprising a series of successively connected separating condensers having open pipe connection from the top of one condenser to the bottom of the next succeeding condenser, and one of the intermediate condensers of the series provided with a pipe to introduce superheated steam and thus raise the temperature therein above the temperature in the last previous condenser through which the vapors pass.

2. An apparatus as described comprising a series of vapor separating condensers and a pipe connecting the top of one condenser with the bottom of the next succeeding condenser and each condenser having a separate outlet at its bottom, in combination with a superheated steam jet arranged to discharge into the bottom of one of the middle of said series of condensers, whereby the heat in the following condenser is increased.

In testimony whereof I affix my signature in presence of two witnesses.

CHAUNCEY B. FORWARD.
